DENTAL HANDPIECE WRENCH

Wolfgang O. Junkel, Mount Prospect, Ill., assignor to
American Hospital Supply Corporation

Filed June 21, 1974, Ser. No. 481,510

Term of patent 14 years

Int. Cl. D24—02

U.S. Cl. D24—1 D

FIG. 2

FIG. 4

FIG. 1

FIG. 5

FIG. 3

FIG. 6

FIG. 1 is a side elevational view of a dental handpiece wrench embodying the design;

FIG. 2 is a top plan view;

FIG. 3 is a bottom plan view;

FIG. 4 is an end view taken from the left end of FIG. 1;

FIG. 5 is an end view taken from the right end of FIG. 1; and

FIG. 6 is a side elevational view similar to FIG. 1 but taken from the opposite side of the wrench.

I claim:

The ornamental design for a dental handpiece wrench, substantially as shown.
